UNITED STATES PATENT OFFICE.

BASIL MAGOR, OF NEW YORK, N. Y.

UNDERFRAME FOR CARS.

1,086,677.

Specification of Letters Patent. Patented Feb. 10, 1914.

Application filed April 6, 1912. Serial No. 688,358.

To all whom it may concern:

Be it known that I, BASIL MAGOR, a subject of the King of Great Britain, and a resident of the borough of Manhattan of the 5 city of New York, in the county and State of New York, have invented an Improvement in Underframes for Cars, of which the following description, in connection with the accompanying drawings, is a specification, like letters on the drawings representing 10 ing like parts.

This invention relates more particularly to improvements in that portion of the underframe which is associated with the draft-rigging and body-bolster, and its object is 15 to provide a simple and efficient construction of underframe which shall be adapted for use in various kinds of cars.

In the drawings, Figure 1 is a plan view 20 of an underframe embodying the improvements; Figs. 2 and 3 are views in transverse section on the lines 2--2 and 3--3 respectively in Fig. 1, Fig. 4 is an end view in elevation, and, Fig. 5 is a view in side elevation of either end of the center sill.

The drawing shows the frame as having channel-iron side and end sills *a* and *b* respectively, and an I-beam center-sill *c* which extends between the body-bolsters *d*. The 30 draft-sills *e* may also be channel-irons, as shown, and are provided one on each side of the center-sill at the ends thereof, continuing the center sill to the ends of the frame. The center-sill is preferably broader or 35 deeper than the frame (see Fig. 2) but tapers at the ends (Fig. 5) to bring them wholly within the plane of the frame (Fig. 3). The last figure shows the construction in the plane of the body-bolsters *d*, from 40 which it will be seen that the latter consist of irons bracing the inner ends of the draft-sills *e* against the sides of the frame. These I-irons may be united to the sides and draft-sills by angles *d'* in the usual manner.

45 To unite the draft-sills to the center-sill, I-irons *m* are employed, one between each draft-sill and the center-sill. The flanges of these irons *m* are riveted or otherwise secured along the ends of the draft-sills on 50 the one hand and along the center-sill on the other, the said irons extending somewhat beyond the end of the draft-sills toward the center of the frame and these inward extensions being securely united to 55 the center-sill. In this way, a particularly

simple and strong connection is made between the center-sill and draft-sills, and between the draft sills and sides of the frame; and at the same time a pair of body bolsters are provided as a part of the bracing- 60 construction for the frame. Further bracing may be provided between the body bolsters *d*, as by the transverse channels *f* and diagonals *g* suitably secured to the side and center-sills by angle plates or the like. 65 These members *f* and *g* may be of less depth than that of the frame, if desired, as shown, for instance, in Fig. 2. It may be observed that, as the drawings are made, the I-irons *m* appear as H-irons; but it will be understood that the term "I-iron" is used here in this inclusive sense.

I claim as my invention:

1. An underframe for cars having a center-sill, a pair of draft-sills one on each side 75 of the center-sill, and an I-iron between each draft-sill and the center-sill to secure the one to the other.

2. An underframe for cars having a center-sill, a pair of draft-sills at each end of 80 the center-sill and lying one on each side of the center-sill, and an I-iron between each draft-sill and the center sill to secure the draft-sills to the center-sill.

3. An underframe for cars having an I- 85 beam center-sill, a pair of channel-iron draft-sills at each end of the center-sill and lying one on each side of the center-sill, and an I-iron between each draft-sill and the center-sill and extending beyond the draft-sills toward the center of the frame to unite the draft-sills to the center-sill.

4. An underframe for cars having an I-beam center-sill tapered at the ends and terminating at points within the ends of the 95 frame, a pair of channel iron draft-sills at each end of the center-sill, lying one on each side of the center-sill and continuing the center-sill to the ends of the frame, an I-iron secured between each draft-sill and the center-sill, and bracing irons forming the body-bolsters extending from the inner ends of the draft-sills to the sides of the frame. 100

In testimony whereof, I have signed my name to this specification, in the presence of 105 two subscribing witnesses.

BASIL MAGOR
